FRANK G. FOWLER, OF ALTOONA, PENNSYLVANIA, ASSIGNOR TO WALTER P. MURPHY,
OF CHICAGO, ILLINOIS.

VESTIBULE-DIAPHRAGM BUFFER-SPRING. **REISSUED**

1,299,929.

Specification of Letters Patent. Patented Apr. 8, 1919.

Application filed August 30, 1916. Serial No. 117,746.

To all whom it may concern:

Be it known that I, FRANK G. FOWLER, a citizen of the United States, residing at Altoona, in the county of Blair and State of Pennsylvania, have invented certain new and useful Improvements in Vestibule-Diaphragm Buffer-Springs, of which the following is a specification.

This invention relates to a buffer spring which is interposed between the end wall of a vestibuled passenger car and the upper portion of the diaphragm face plate of the vestibule for the purpose of holding the face plate in proper place against the corresponding element of the vestibule of the adjacent car and for returning said face plate to its normal position after it has been displaced, for example, in rounding a curve. The spring used in this connection is ordinarily a compound leaf spring, for example, a semi-elliptical spring which is usually fastened at its middle to the diaphragm face plate and has the extremities of its master leaf slidably engaged with the end wall of the car, by confining means which, while permitting the free movements of the ends of the spring when the latter is compressed and expands, subjects the spring to a strain when the diaphragm plate is displaced, which tends to return the plate to its proper position after the cars have resumed their normal alignment.

Because of the inequalities of the road bed and consequent movements of the end of the car both vertically and sidewise, the diaphragm plate of a car vestibule is subject to almost continuous vibration while the car is in service. This subjects the free ends of the spring to a constant rubbing against the surfaces with which they contact, the friction of which soon wears such surfaces. My present invention has for its object to provide the means for confining the ends of a spring of this sort with removable wear plates which can be readily replaced when they are worn sufficiently to make replacement desirable.

The invention is illustrated in a preferred embodiment in the accompanying drawing, 50 wherein

Figure 1 is a fragmentary view showing, in elevation, the end of a vestibule railway passenger car provided with a diaphragm buffer spring, with its extremities engaged

with the end wall of the car by the devices 55 of my invention.

Fig. 2 is a plan view, partly in section, of the end of the car, showing, however, only such elements of the car structure as are here concerned.

Fig. 3 is a view, in perspective, of one of the devices for providing engagement between the spring and the car.

Figs. 4 and 5 are similar views of the parts of one of these devices.

Like characters of reference indicate like parts in the several figures of the drawing.

In the drawing, 10 indicates the end wall of the car which is shown as of steel construction, and 11 the diaphragm face plate. The buffer spring is indicated at 12. The spring is shown as anchored at its middle point to the diaphragm face plate by rivets 13. Its extremities have a sliding engagement with the end wall 10 of the car. This 75 is the customary arrangement of the spring, although it will be possible to reverse its position so that the rigid attachment should be made to the car wall instead of to the face plate.

The master leaf 14 of the spring has its extremities bent over, as indicated at 14^a. The devices for providing the sliding engagement between the extremities of the spring and the car wall consist, in each case, 85 preferably of a wear plate 15 and a tapered channel-shaped housing 16, the latter being provided with flanges 17 and the two parts of the device being drilled with holes 18, 19, whereby they may be riveted or otherwise 90 secured together as shown in Fig. 3.

Preferably the area of the wear plate is greater than that of the housing, so that when the housing is secured to the wear plate the latter will have marginal attaching 95 flanges 20 which are drilled at 21 for the rivets or other means employed for attaching the wear plate to the end of the car.

When the constant rubbing of the spring against plate 15 has worn the plate down, it is a simple matter to cut the attaching rivets or other fastening devices, and remove the wear plate and housing member from the car. If the housing member is uninjured, it can be used again in connection with a new 105 wear plate.

I claim:

1. The combination with the end wall and

diaphragm face plate of a vestibuled rail-
way car, of a leaf spring anchored to one of
the aforesaid elements of the car with an ex-
tremity slidably engaged with the other of
5 such elements, and confining means for the
free extremity of said spring which permits
said sliding movements while subjecting the
spring to a strain when the diaphragm face
plate is displaced from its normal position,
10 such means comprising a housing member
extending around the said extremity of the
spring, a wear plate comprising a flat sheet
of material, and means, capable of ready de-
tachment, for securing the wear plate and
15 housing member to the last mentioned ele-
ment of the car.

2. The combination with the end wall and
diaphragm face plate of a vestibuled rail-
way car, of a leaf spring anchored to one of
the aforesaid elements of the car with an
extremity slidably engaged with the other
of such elements, a flat wear plate against

which said extremity of the spring bears,
means for detachably securing said wear
plate to said last mentioned element of the
car, a housing member to surround the ex-
tremity of the spring comprising a sheet of
25 metal pressed to form a channel of dimin-
ishing depth and outstanding flanges at the
sides of said channel, and means for secur-
ing said flanges to said wear plate.

3. A device for attaching the end of a
buffer spring of a vestibule diaphragm to a
car, comprising a housing member adapted
to extend around the extremity of the spring,
35 and a flat wear plate to which said housing
member is secured having margins surround-
ing said housing member, and means engag-
ing said margins for removably securing
said plate to the car end.

FRANK G. FOWLER.
